UNITED STATES PATENT OFFICE.

HORACE PFOUTS GORMAN, OF HAZLETON, PENNSYLVANIA.

DISPENSING LIQUID-HOLDER.

No. 886,596.

Specification of Letters Patent.

Patented May 5, 1908.

Application filed May 15, 1907. Serial No. 373,758.

To all whom it may concern:

Be it known that I, HORACE PFOUTS GORMAN, a citizen of the United States, residing at Hazleton, in the county of Luzerne and 5 State of Pennsylvania, have invented a new and useful Dispensing Liquid - Holder, of which the following is a specification.

This invention has reference to improvements in dispensing liquid holders, designed 10 more especially for the semi-automatic dispensing of liquid soap or similar material.

The invention consists essentially of a suitable receptacle with a simple means for removably attaching the same to a support, 15 and, in addition, the receptacle is provided with a pump or soap-expelling means so arranged that a pressure will be established to force the soap from the receptacle in such quantities as may be deemed expedient. 20 Provision is made whereby the soap will be directed upon the hand of the user within a circumscribed area, and means are provided whereby the device may be adjusted to regulate the pressure established before the soap 25 is allowed to escape and also to regulate or limit the amount of soap expelled at each operation of the device.

The invention will be fully understood from the following detailed description taken 30 in connection with the accompanying drawings forming part of this specification, in which,—

Figure 1 is a central, vertical section through the device; and Fig. 2 is a face view 35 of the wall support, with the removable bracket for the soap-holder shown in section.

Referring to the drawings, there is shown a receptacle 1 which may, if desired, be of glass or may be constructed of metal. This receptacle is in the form of a jar or bottle having a wide mouth with exterior screw-threads on the neck, and to this threaded portion is adapted a cover 2, also formed with screw-threads, while the interposed gasket 3 of rubber or any other suitable material serves to 45 render the junction between the cap 2 and the neck of the receptacle fluid-tight.

Surrounding the receptacle is a collar 4 made of a band of metal having its free ends 50 brought into juxtaposition and there held by a bolt or rivet 5 while the extreme ends are bent at right angles, as shown at 6—6 so as to enter between two stiff wings 7—7 with the ends 6 resting behind the same. These 55 wings are formed as upturned bottom exten-

sions of a wall plate 8 provided with suitable perforations 9 for screws or other fastening means, while a pivoted latch member 10, which may be made of wire riveted to the wall plate 8 but capable of turning thereon, is 60 provided for holding the ends 6 of the collar 4 from accidental displacement from behind the wings 7. The latch may be formed of a single piece of stiff wire bent on itself near one end to form a loop 11 with the free end up-turned, as shown at 12, the loop being of sufficient size to extend across the wall plate 8 to engage and bear against the upper edge of the end pieces 6, while the upturned end 12 permits the latch to be moved about its pivot 65 without catching on these ends 6, and the loop which, as shown, is open-ended, has sufficient resiliency to establish the requisite frictional contact with these ends 6 to hold the loop securely in place in the locked position. 70

Returning, now, to the consideration of the cap 2, it will be seen that the latter is dished at its center, as shown at 13, and projecting from this dished portion into the interior of the receptacle 1 is a cylinder 14, open at the end remote from the cap 2 and there threaded to receive a threaded closure 15, while at a point adjacent to the dished portion of the cap 2 this cylinder 14 is provided 85 with a through slot 16.

Passing through the central portion of the dished section of the cap 2 is a sleeve 17 entering the cylinder 14 for a short distance, and exterior to the cap 2 this sleeve is provided with diametrically opposite, longitudinal slots 18 extending to the end of the sleeve remote from the junction of the sleeve with the dished portion 13 of the cap 2. This sleeve 17 is concentric with the cylinder 14, 90 and extending through this sleeve and movable therein there is a tube 19, open at both ends. One end 20 of this tube extends above the upper end of the sleeve 17 and is there threaded and carries a piston 21 arranged to move snugly within the cylinder 14. The other end of the tube 19 extends 95 for a distance below the lower end of the sleeve 17 and its bore at this lower end flares, as shown at 22. The tube may be of constant bore throughout except at the flared end. Located at a distance below the lower or flared end of the tube is a ring 23 having its axis coincident with the axis of the tube, and this ring is connected to said tube by two 100 105 110 115

arms 24 which may be brazed or soldered to said tube. These arms, at their junction with the tube, are shaped to enter the slots 18 and the construction is such that these 5 arms at this point are always within the slots but are capable of moving longitudinally within said slots.

The sleeve 17 forms a long bearing for the tube 19, and the slots 18 permit the travel of 10 the tube together with the arms 24 along said sleeve for a distance determined by the length of the slots 18 in one direction, except as hereinafter described, and in the other direction the travel of this tube is limited by 15 the engagement of the piston 21 with the end of that portion of the sleeve 17 which enters the cylinder 14.

Arranged to travel within the tube 19 is a cylindrical plug 25 on one end of a rod 26 extending upward through the tube and centrally through the cylinder 14 and closure 15. This rod is threaded at the upper end for a distance within the cylinder and to the extreme upper end, as indicated at 27, and the 25 passage in the closure 15 is formed with a nut through which the rod is screwed, while within the cylinder 14 on the screw-threaded portion 27 of this rod there is applied a screw collar 28. Within the cylinder 14 is confined 30 a spring 29, bearing at one end against the closure 15 and at the other end against the piston 21. Now, let it be assumed that the rod 26 is screwed through the closure 15 to the desired position, with the plug 25 within 35 the tube 19 at a point somewhat removed from the flaring open end 22. And also let it be assumed that the collar 28 is adjusted on the threaded end 27 of the rod 26 to some desired position, and that the receptacle 1 contains 40 liquid soap.

The parts are so proportioned and adjusted that when the piston 21 is resting on the upper end of the sleeve 17 the upper end of the slot 16 is uncovered to put the interior 45 of the cylinder 14 into communication with the interior of the receptacle 1. Under these conditions, a certain amount of liquid soap will flow into the interior of the cylinder 14 above the piston 21 and also down into the 50 tube 19 until stopped by the plug 25. Now, suppose that a person desires to procure a charge of soap upon one of the hands. The hand of the user is placed against the under side of the ring 23, which, in practice, is of 55 such size as to be easily contained on the palm of the hand, and pressure is exerted to force the ring 23 upward, it being understood that the whole device is in the position shown in the drawing. The first result of this movement is to move the piston 21 past the upper 60 end of the slot 16 and so close the cylinder 14 against communication with the interior of the receptacle except below the piston 21. At the same time the tube 19 is also moved 65 upwardly but the plug 25 is so located that

the piston 21 must move for a considerable distance into the cylinder 14 before the tube 19 will move to a position to be above the plug 25. The result of this is that the air within the cylinder 14 is compressed to an extent and the liquid soap contained therein is put under stress. Now, as soon as the plug 25 has, relatively speaking, passed through the flared end 22 of the tube 19 the soap will be forced out through the lower end of the 70 tube under the force exerted by the air pressure within the cylinder 14, and this flow of soap under stress continues so long as the piston 21 is moved upward and there still remains soap within the cylinder 14 or tube 75 19. The upward movement of the piston 21 may be continued until stopped by the collar 28, the spring 29 being at the same time correspondingly compressed. Now, when the hand of the user is removed from the ring 23 80 the expansive force of the spring 29 comes into action and causes the movement of the tube 19 to its normal position until the piston 21 is arrested by contact with the upper end of the sleeve 17. In the meantime the plug 90 25 has again entered the tube 19 through the flaring end thereof, being assisted in this movement not only by the shape of the flaring end but the junction between the plug 25 and rod 26 may be shaped as indicated at 95 30 and conform in a manner to the flaring end of the tube.

By suitably screwing the rod 26 to a greater or less extent through the closure 15 the relative position of the plug 25 within the 100 tube 19 may be adjusted so that a greater or less compression of the air within the cylinder 14 may be established before the soap is allowed to escape through the lower end of the tube 19, and by suitably adjusting the collar 105 28 the extent of movement of the tube 19 and piston 21 may be controlled.

As soon as the plug 25 has entered the tube 19, which is before the piston 21 has reached the slot 16, there is created a partial 110 vacuum in the cylinder 14 as the piston descends, and, consequently, when the upper end of the slot 16 is opened to establish communication between the interior of the upper end of the cylinder 14 and the interior of the 115 receptacle 1, the soap within the receptacle will rush into the cylinder, due to the partial vacuum therein.

I claim:—

1. A liquid dispensing apparatus comprising 120 a suitable receptacle for the liquid, a fixed supplemental container for the liquid within the receptacle, means for permitting access from the receptacle to the supplemental container, a movable piston within the supplemental container and arranged to close the latter to the main receptacle and to establish an air pressure within the supplemental container, and positively operated means independent of the air pressure for opening the 125 130

container to permit the discharge of liquid therefrom after the air pressure has been established therein.

2. A liquid dispensing apparatus comprising a suitable receptacle for the liquid, a fixed cylinder therein closed at both ends and having a port near one end open to the main receptacle, a piston movable in said cylinder normally unclosing the port but arranged to close the port when moved in the proper direction in said cylinder, a hollow piston rod for the piston, and a plug or closure normally housed in said piston rod and arranged to be moved out of the same after the piston has completed a predetermined range of movement.

3. A liquid dispensing apparatus comprising a suitable receptacle for the liquid, a closed cylinder in said receptacle provided with a port near one end, a piston within the cylinder normally unclosing said port, a hollow piston-rod connected to said piston, a slotted guiding sleeve for said hollow piston-rod, a fixed plug normally within the hollow piston-rod and past which the rod is movable, and a hand-rest fast on said piston-rod in the axial line of the same.

4. A liquid dispensing apparatus comprising a suitable receptacle, a cylinder therein closed at both ends and having a port near one end, a piston movable in said cylinder and provided with a hollow piston-rod, a plug for said hollow piston-rod normally contained therein, and a threaded rod carrying said plug and extending through a nut formed in one end of the cylinder.

5. A liquid dispensing apparatus consisting of a suitable receptacle, means therein

for putting the liquid to be dispensed under pressure, an outlet for the liquid under pressure, a closure for said outlet, positively operated means timed to open the outlet after a predetermined pressure has been established, and means for adjusting the closure operating means to vary the time relation of discharge.

6. A liquid dispensing apparatus comprising a suitable receptacle, a single stroke liquid discharge pump therein, means for adjusting the stroke of the pump, a discharge means coöperating with the pump and positively operated by the movement of said pump, and an adjusting means for establishing the relation between the movement of the pump and the time of discharge.

7. A liquid dispensing apparatus comprising a suitable receptacle, a pump therein having a piston movable in one direction under the impulse of the hand, a spring for returning the piston to its normal position, means for limiting the extent of movement of the piston, a closure for the discharge end of the pump arranged to open said discharge end after a predetermined movement of the pump, and means for adjusting the time relation between the movement of the pump and the opening of the discharge end of the pump.

In testimony that I claim the foregoing as my own, I have hereto affixed my signature in the presence of two witnesses.

HORACE PFOUTS GORMAN.
